[57] **CLAIM**

The ornamental design for a hard disk drive carrier, as shown and described.

DESCRIPTION

FIG. 1 is a front top and right side perspective view of a hard disk drive carrier showing our new design; FIG. 2 is a rear bottom and right side perspective view thereof; and, FIG. 3 is an enlarged front elevational view thereof. The undisclosed left side view is identical to the side shown.

FIG. 1

FIG. 2

FIG. 3
